CASKET HANDLE

George M. Clifford, Westfield, Mass., assignor to
Textile Manufacturing Company, Westfield,
Mass., a corporation of Massachusetts

Application March 9, 1937, Serial No. 129,862

3 Claims. (Cl. 16—112)

This invention relates to casket handles. In the past the type of casket handle having the best appearance has had a bar supported rigidly on lugs or supports extending outwardly from the wall of the casket. An excellent appearance can thus be obtained, but in order to get sufficient room for the hands it is necessary that the bar be set out a substantial distance from the wall of the casket, thereby increasing the overall dimensions of the latter. In order to obtain sufficient hand room without increasing the overall dimensions of the casket it has also been proposed to use hinged handles. Former types of hinged handles have been of much poorer appearance than the solid bar type, both because of the design of the hinge and because they have required too great an overall height of the handle supporting structure. A further difficulty with these hinged handles has been that the continuity of the design was broken when the handle was either in lower or raised positions.

The present invention relates to a hinged handle having the appearance of a solid bar handle and taking up no more room in a vertical direction. The invention further permits the use of a single supporting plate instead of the two spaced plates customarily used for handles of the solid bar type. The invention also provides a handle which maintains the continuity of the design in both lowered and raised position. The invention further permits the merging of the design between the fixed and movable parts so that a balanced design and an ample swinging movement of the handle can be obtained with a relatively small overall height and thickness. The invention also permits the handle structure being secured to the wall of the casket by means which are entirely concealed from view.

Referring to the drawings:

Fig. 1 is an elevation, partly broken away, showing the improved type of handle;

Fig. 2 is an end elevation with the bar broken away;

Fig. 3 is a section on line 3—3 of Fig. 1;

Fig. 4 is a section on line 4—4 of Fig. 1;

Fig. 5 is a central section through a modified form of handle structure;

Fig. 6 is a section on line 6—6 of Fig. 8;

Fig. 7 is a section on line 7—7 of Fig. 8; and

Fig. 8 is a section of the bar supporting arm.

The handle supporting structure consists of a base plate 10 which may be made in one or more sections. At the ends of this plate are hinge supporting members 11 provided with parallel ears 12. The plate, the hinge supporting mem-

bers, and the ears are preferably formed from some easily moldable metal such as a lead antimony alloy into which are cast steel braces 13. These braces have upstanding portions 14 which as shown in Fig. 4 lie in the center of the ears 12.

At each end of the plate is mounted, in a manner to be described, a handle supporting arm 15 having a portion of reduced height 16 extending between the ears 12. The top of the portion 16 is preferably made flush with the members 11 and the two parts are designed so that the arms 15 and the supporting members 11 merge into a unitary design. Looking from the side, as in Fig. 2, it will be seen that the parting line 17 between the arms 15 and the ears 12 is positioned diagonally so that when the handle is down there is no gap apparent and still the handle can be readily raised.

The arms 15 are also formed of a moldable alloy cast around a reinforcing piece 18 of steel into which a square hole 19 is formed for the reception of the bar 20. The ears 12, the upstanding portions 14 of the braces 13, the part 16 of each arm 15, and the reinforcements 18, are all 25 perforated to receive pintles 21 by which the arms are pivoted. As will be seen in Fig. 3, the members 11 are cut away internally, preferably on a curve, so that the arms will have room to move and the continuity of the design as viewed 30 from the front will be preserved in any position of the handle. To limit the upward movement of the arms the reinforcements 18 are provided with lugs 22 which engage the ends of the flat 35 portions of the braces 13 as will be apparent from the dotted lines in Fig. 3. These flat portions of the braces 13 and the plate 10 underneath them are perforated with countersunk holes for securing screws or bolts 23. When the arms are lowered these screws are completely concealed 40 from view.

It will be noted from the above description that the outer sides of the arms 15 are flush with the outer sides of the ears 12 giving the arms and the supporting members 11 the appearance of one 45 continuous member. The same continuity is maintained whether viewed from the side or the front. It will be further noted that practically the entire height of the plate 10 can be used for the arms 15, depending only on the extent of 50 members 11 which is desired for design purposes; so that the maximum spacing of the handle from the casket wall can be obtained when the handle is raised, together with a minimum overall height of the plate and a minimum thick- 55

ness of the assembly when the arms are lowered. It will also be noted that the ears 12 terminate at the slanting line 17 well above the bar 20, so that when the handle is down the bar is positioned close to the plate 10 without interference from the ears. This provides a very compact device which does not require any recessing of the supporting structure to accommodate the bar when in its lowered position.

10 The modification shown in Figs. 5 to 8 permits an even greater degree of separation of the bar from the casket wall without increasing the overall dimensions of the handle structure when the bar is down. In this case, as previously, the base 15 is formed of a casting 30, preferably hollow, in which steel reinforcements 31 are embedded near its ends. The ends of the casting are enlarged at 32, and into these enlargements pass spaced pairs of lugs 33 arranged as in the case of the ears 12 20 previously described. Between each pair of lugs extends a stationary pivot pin 34 which is also embedded in the casting, the latter being cut away at 35 to form parallel ears 36 similar to the ears 12 previously described. An arm 37, 25 formed of a suitable casting and carrying centrally thereof a brace 38 of sheet steel, is positioned between each pair of ears; and its brace is provided with a curved slot 39 through which the pivot 34 passes. Each brace 38 also carries a 30 pin 40 passing through a slot 41 in a link 42 pivoted at 43 to the brace 31.

As the bar 43' is drawn outwardly from its supporting structure, its slot 39 will slide on the pivot 34 until the position of Fig. 7 is reached, at 35 which the pin 40 reaches the end of slot 41. The arm will be held firmly by the pivot 34 and the link 42 instead of by the pivot 21 and the abutment 22 as in the previous case. On the reverse movement the end of the arm will slide into the 40 hollow interior 45 of the enlargement 32, causing the overall height of the collapsed handle to be less than would be the case were a fixed pivotal connection to be used. If desired, an abutment 46 on the end of each reenforcement

38 may be employed as in the preceding modification to assist in supporting the arm in its extended position.

What I claim is:

1. A casket handle comprising a hollow supporting structure having two pairs of spaced parallel ears, a pivot extending between each pair of said ears, an arm mounted between each pair of ears and having an arcuate slot to receive the pivot, a bar extending between said arms, and 10 connections between the arms and the supporting structure to constrain the arms to move on said pivots further into the hollow of the supporting structure when the handle is moved to inactive position.

2. A casket handle comprising a hollow supporting structure having two pairs of spaced parallel ears, a pivot extending between each pair of said ears, an arm mounted between each pair of ears and having an arcuate slot to receive the pivot, and a link connecting each arm and the supporting structure and having a pin and slot connection with the arm to constrain the arms to move on said pivots further into the hollow supporting structure when the handle is moved 15 to inactive position and to limit the pivotal movement of the arms away from the supporting structure.

3. In a casket handle, a plate adapted to be secured to the casket wall and formed to provide 20 parallel spaced ears with their ends beveled in a direction downwardly and towards the casket wall, an arm of a width equal to the overall width of the spaced ears and shouldered laterally to provide a portion of reduced width extending 25 between the ears, the shoulders of said arm being beveled to correspond with the bevels at the ends of the spaced ears, a pintle connecting the arm with said ears for pivotal movement, and a handle carried by said arm, whereby when the 30 handle is in lowered position the lateral surfaces of the arm merge into the lateral surfaces of the ears.

GEORGE M. CLIFFORD.
